UNITED STATES PATENT OFFICE

2,057,755

CENTRIFUGAL DRIER

Clarence M. Wilderman, Moscow, Idaho

Application September 18, 1934, Serial No. 744,469

2 Claims. (Cl. 210—69)

My present invention relates to an improved centrifugal drier which, while adapted for drying various commodities, is especially designed for the purpose of removing excess moisture from the exterior surfaces of peas, beans, etc., as well as for drying various grains. The apparatus is successfully employed in the operation of separating excess moisture from the exterior surfaces of peas that have been washed, or subjected to a bath, and this drying of the peas is accomplished without loss in quantity when passing through the apparatus, and without marring the husks or wrappers of the peas, so that the commodity coming from the drier is in proper condition for packing and shipping without necessity for further treatment.

In carrying out my invention I employ a rotary drying drum having a vertical axis and a rotary conveyer or carrier within the rotary drum, and these members are mounted in a stationary or fixed drum and operated to develop centrifugal action by means of which the excess moisture is separated from the exterior surfaces of the peas. The invention consists in certain novel combinations and arrangements of parts whereby an efficient, compactly arranged, high speed apparatus is attained at comparatively low cost of manufacture, and operated at low cost of maintenance.

In the accompanying drawings I have illustrated one complete example of the physical embodiment of my invention which has proven highly successful in operation, but it will be understood that various changes may be made in this exemplifying structure, within the scope of my appended claims, without departing from the principles of my invention.

Figure 1 is a view in side elevation of a drier embodying my invention, broken away for convenience of illustration.

Figure 2 is a vertical central sectional view of the drier with some parts in elevation.

Figure 3 is a transverse sectional view at line 3—3 of Figure 2.

In carrying out my invention I utilize an upright, open top cylinder 1 of suitable size or dimensions, which is provided with a flanged bottom ring 2 that is rigidly fixed to the cylinder, and a water drain-pipe 3 is provided at the bottom of the cylinder for disposal of water that may accumulate in the interior of the cylinder, due to the centrifugal drying action of the device.

Within the bottom ring 2 of the cylinder is fixed a discharge bottom for the peas, which discharge bottom comprises an outer circular flange 4, a concentric inner flange 5 forming a central open-

ing in the bottom, and an annular bottom 6, which, as shown is located below the bottom ring 2 of the cylinder. This circular discharge bottom is provided with a pair of discharge chutes that are formed by the use of two horizontal, spirally arranged, partitions 7 and 8 that terminate in tangentially arranged and oppositely opening delivery or discharge spouts 9 and 10, which, as shown in Figure 3, project beyond the periphery of the stationary cylinder, for disposal of the 10 dried peas.

The stationary cylinder and its discharge bottom are supported on a central base or stand 11, and the latter may in turn be supported on any suitable object, as the base-board B. The stand 11 is fashioned with a bearing block 12 which extends upwardly in the open center of the discharge bottom of the cylinder, and the bearing block is equipped with two vertically spaced, horizontally arranged bearings 13 and 14 in which the stepped end 15 of the upright shaft 16 is supported. At its upper end this shaft is journaled in a complementary bearing 17, the three bearings providing a substantial support for the rotary shaft which is operated at comparatively 25 high speed, in some instances at 500 revolutions per minute. On the vertical shaft is mounted a spirally arranged conveyer or carrier 18 for the peas with its flights so arranged that the peas will naturally flow from top to bottom of the 30 spiral-carrier and be discharged in the annular discharge bottom of the stationary cylinder, and from thence pass through the tangential discharge spouts.

The spiral carrier is closely surrounded by a 35 rotary drum 19, of cylindrical shape, and of less diameter than the stationary cylinder, in order to form a water space within the cylinder and about the rotary drum. This rotary drum is fashioned with perforations or openings 20, preferably arranged in spaced vertically arranged rows or tiers that extend from substantially the top to the bottom, of the rotary drum and afford communication between the interior of the rotary drum and the annular water space in the cylinder surrounding the drum.

The bottom of the rotary drum is fashioned with a spider frame which comprises a central disk 21 loose on the shaft 16 and located below the lower end of the spiral carrier. From this disk or hub-plate 21, which is rigid with the rotor of the upper bearing 14, spokes 22 radiate across the open top of the discharge bottom of the cylinder, and at their outer ends the spokes are rig- 55

idly fastened in suitable manner to the bottom ring 23 of the rotary drum.

By this construction and arrangement of parts it will be understood that the spiral carrier and its shaft, and the rotary drum closely surrounding the carrier, are both supported to revolve in one and the same direction, but the drum revolves at a higher speed than the carrier. If the carrier is revolving at 500 revolutions per minute, the drum revolves at approximately 600 revolutions per minute, but it will be understood that these rates of speed may be varied, and the proportion between the speeds may also vary, to accommodate the drier to varying conditions.

15 The upper end of the rotary drum is closed by a circular head 24, and a sprocket wheel 25, centrally located on the head, and fixed thereto, revolves around a bearing collar 26 that is rigidly attached to a circular or cylindrical hood 27, the lower, open end of which depends through a complementary central opening in the head 24 of the rotary drum. A diagonally arranged feed hopper or chute 28 for the peas is fashioned on the hood between the bearing 17 and the head of the rotary drum, through which the peas are fed, passing through the hood and dropping to the upper flight of the spiral rotary carrier.

20 The hood is rigidly supported at the end of a horizontal arm 29 which is rigid with the upright post 30 of the appliance and the post is provided with a suitable base to insure its stability. An electric motor for driving the rotary parts is designated as 31 and affixed to the lateral arm 32 which projects from the post 30 in direction opposite to that of the arm 29, and the motor is provided with a pair of driving pulleys 33 and 34 for transmission of power to the rotary carrier and the rotary drum. A belt 35 on pulley 33 and a similar belt 36 on pulley 34 transmit power to 25 the pulleys 37 and 38 respectively that are journaled on the upright shafts 39 and 40 which two axially aligned shafts are journaled in the upright bearing sleeve 41 rigid with the post 30.

30 Shaft 39 transmits power through its sprocket wheel 42 and chain 43 to the sprocket wheel 44 on the upper end of the carrier shaft 16 to revolve the carrier; and shaft 40 transmits power through its sprocket wheel 45 and chain 46 to the sprocket 25 rigid with the head of the rotary drum for revolving the drum. Any other suitable arrangement for driving or revolving the carrier and the drum may be used, but in all cases provision is made for revolving the drum at a higher speed than the carrier, although the speeds of these parts may be changed under varying conditions.

35 As the peas are fed to the rapidly revolving carrier a continuous stream of peas flows down the spiral carrier and the centrifugal action of

the carrier moves the peas to the outer edge of the spiral flights, some of the peas lightly contacting with the more rapidly revolving rotary drum, and this contact increases the speed of movement of the stream of peas down and around the spiral flights. The peas are thus separated and spread outwardly in the carrier and the moisture or drops of water on the exterior surfaces of the peas are thrown outwardly by centrifugal action to the edges of the spiral flights and pass 10 through the openings in the cylindrical wall of the rotary drum to the annular space within the cylinder.

15 Any excess moisture that may cling to the peas after they have been washed is thus separated, either by evaporation, or by centrifugal action, and in the latter case the moisture falls to the bottom of the cylinder and is drained off through the pipe 3.

20 By the time the peas have traversed the length of the carrier, from top to bottom, all exterior or excess moisture has been eliminated therefrom, and they are then delivered by the carrier into the annular bottom of the cylinder onto the partitions 7 and 8, and by momentum, are passed out 25 through the tangentially arranged spouts 9 and 10 for subsequent packing and shipping.

25 Having thus fully described my invention, what I claim as new and desire to secure by Letters Patent is:—

30 1. In a centrifugal separator, the combination with a fixed outer cylinder having a bottom portion comprising a pair of upright spaced inset, concentric flanges and bottom forming an annular discharge chamber, a pair of arcuate spirally arranged partitions in said chamber, and tangentially arranged discharge spouts from said chamber, of a perforated rotary drum mounted in the cylinder and operating means therefor, a rotary carrier surrounded by said drum, and means for revolving said carrier.

35 2. In a centrifugal separator, the combination with a stationary cylinder having a bottom portion comprising a pair of spaced, concentric flanges and bottom forming an annular discharge chamber and said bottom having a central opening, a pair of arcuate, spirally arranged partitions in said annular chamber, a base for the bottom and a bearing block rigid with the base and located in said opening, an upright shaft journaled in said bearing block and a spirally arranged carrier fixed on the shaft, a perforated rotary drum located within the cylinder and having a bearing on the lower end of said shaft, a bearing for the upper end of the drum, means for revolving the drum, and means for revolving the carrier.

40 CLARENCE M. WILDERMAN.
